UNITED STATES PATENT OFFICE.

ERNEST K. POST, OF COLLINGSWOOD, NEW JERSEY.

CONNECTER FOR TRACK CIRCUITS AND TRAIN-CONTROL SYSTEMS.

Application filed October 23, 1925. Serial No. 64,333.

My invention relates to connectors for use primarily in signal circuits and train-control systems where a stranded wire is to be connected to any insulated wire of the circuit.

The purpose of my invention is to simplify the connections between stranded wire conductors and the wires of track circuits.

A further purpose is to improve the contact with the stranded wire in connection with such circuits as track circuits, to protect against pulling out of the stranded wire and to avoid nicking the stranded wire where it enters the terminal.

A further purpose is to reduce the number of parts where stranded wire terminals are to be connected with other wires of the circuits.

A further purpose is to reduce the number of removable contacts between a stranded wire terminal and the wire connecting with it.

A further purpose is to provide bolt connection between a stranded wire and a terminal therefor, and to grip the circuit wire with which engagement is to be made through operation of the bolt.

Further purposes will appear in the specification and in the claims.

I prefer to illustrate one form of my invention only, selecting a form which has proved to be practical, efficient, inexpensive and reliable and which at the same time well illustrates the principles involved.

Figure 1 is an elevation, partly diagrammatic, showing one of my connectors within a track circuit.

Figure 2 is an enlarged view, partly sectional of a portion of the structure of Figure 1.

Figure 3 is a section of Figure 2 taken upon line 3—3.

Figure 4 is a perspective showing parts from Figure 2 in disassembled position.

Figure 5 is a top plan view showing a second setting of my invention in a different track circuit.

Figure 6 is a section of Figure 5 upon line 6—6.

Figure 7 is an elevation partly in section and is a fragmentary section of a bolt and stranded wire connection.

In the drawings similar numerals indicate like parts.

Train-control systems are coming into use

widely and track circuits for signalling have 55 been used in large numbers for many years and in great variety by the railways.

Because of the great convenience of plug connection with the rails the use of plugs is very general. The vibration of the rails is 60 so excessive that the connections with these plugs are made to stranded conductors rather than to solid wires and these stranded conductors must in turn be connected to the circuit wires by which the source of 65 energy, relay or other apparatus, is included in the circuit.

The circuit wires so usually comprise insulated solid conductors that they will be treated herein as if this were always so. 70 However a stranded conductor could also be gripped well by my construction and, if there be no insulation on the circuit wires the counterbores for the insulation would not be needed. Suitable means would then 75 be provided against breakage of the conductor at the edge of the connector.

My invention has to do wholly with the connection between the stranded conductors and the circuit wires in whatever setting otherwise and whatever the source of energy, relay or other apparatus which is to be included in the circuit.

In Figure 1 the circuit extends from a rail through the plug 10 driven into a hole 85 in the rail, a stranded conductor 11, connector 12, circuit wire 13, insulated at 14, relay 15 and wire 16 back through a corresponding connector, stranded conductor and plug to another rail, not shown.

In Figure 5 an insulated rail joint is shown at 17. Rails 18 are broken away to show the webs 19 and plugs 20, with or without clips 21. Stranded wires 22 are permanently united at one end each to the plugs 95 and at the other ends 23 are united to connectors 12 from which conductors 24 extend to battery or other source of energy 25 and back by corresponding connection to another rail.

Parts of the stranded wires, the connectors and the circuit wires are carried in a conduit 26.

I have found that the stranded wire, which is ordinarily of steel, may be welded at its 105 end to the end 27 of a bolt 28. This bolt fits within the connector 12, forcing forwardly the clutch comprising split jaws 29

into the converging tapered opening 30 so as to secure pressure contact and good gripping engagement between these parts and the end 31 wire 13.

- 5 This avoids reliance upon contact with the stranded iron wire by pressure merely, as has hitherto been thought to be necessary and makes it possible to use this bolt to tighten a wedge-gripping device upon the 10 track circuit wire, greatly reducing the electrical resistance of the connection, simplifying the parts and obtaining a more secure and permanent grip.

- 15 The connector 12 is not only bored for the tapered opening 30 but is counterbored at 32 and 33 at opposite ends, one of the counterbores being threaded to receive the bolt 28 and that at the other end accommodating the insulation 14 surrounding conductor 13.
- 20 The conductor 13 is stripped of insulation sufficiently to permit clamping engagement with it.

Within the tapered opening 30 fit the tapered clutch jaws 29 which are most desirably made in a single piece in order to avoid trouble from slipping of the parts or loss of the parts and to cheapen the manufacture. The jaws surround a central opening 34 within which the end 31 of the conductor 30 13 is intended to fit, the conductor being sufficiently near the diameter of the opening to be gripped firmly by the jaws when the clutch member is forced into the opening by relative turning of bolt and connector.

35 When the clutch is made in a single piece it is slotted at 35 to allow circumferential compression for the purpose of gripping the conductor.

In operation, the conductor is stripped of 40 its insulation at one end sufficiently to permit the end of the conductor to pass into the central opening of the clutch which is put in from the left in Figure 2. Either the bolt or the connector is turned, one with respect to the other, until the clutch is firmly gripped against the conductor end 31 on the inside and against the wall of the tapered opening 30 on the outside. The resistance of the clutch member causes the 45 outwardly facing surfaces of the bolt thread to engage tightly against the inwardly facing surfaces of the threads within the connector, giving a large surface there for electrical contact, preventing access of moisture and consequently preventing rust between the surfaces.

The connector is given a noncircular section at 38 to facilitate the relative turning of the connector and bolt.

50 It will be evident that my disclosure will suggest to those skilled in the art other forms and places in which my invention may be used with or without copying the form of the invention illustrated and it is, therefore, my purpose to cover all such forms

and uses as come within the reasonable spirit and scope of my invention.

Having thus described my invention, what I claim as new and desire to secure by Letters Patent is:

70 1. In a signal circuit or train-control system, a stranded wire, a threaded terminal permanently attached to it, a clutch connector having a threaded opening within which the terminal fits to tighten the clutch 75 and a conductor adapted to fit within and be clamped by the clutch.

2. In a signal circuit or train-control system, a stranded wire, a bolt permanently united thereto, a connector body having a 80 tapered bore and a counterbore threaded to receive the bolt, a clutch member fitting within the tapered bore adapted to be tightened 85 therein by the bolt and a conductor adapted to fit into and to be gripped by the clutch member.

3. In a signal circuit or train-control system, a stranded wire, a plug permanently united to one end of the wire and a bolt 90 permanently united to the other end thereof, a connector body having a tapered bore, a threaded counterbore adapted to receive the bolt and a second counterbore at the opposite end from the first counterbore, a clutch member fitting within the tapered 95 bore and adapted to be tightened by the bolt and an insulated conductor whose insulation is adapted to fit within the second counterbore and whose wire is adapted to fit into and be gripped by the clutch member. 100

4. In a device of the character stated for joining a stranded cable and a single conductor, the combination of a bolt to which the cable is permanently united by fusion, a connector having a tapered bore and, adjacent its larger end a threaded counterbore into which the bolt fits, and a clamping device fitting within the tapered bore adapted to engage the single conductor and to be gripped against it by the pressure of the bolt, whereby the bolt and clamping member form parts of the electric connection between the stranded wire and the single conductor. 110

5. In a device of the character stated for 115 electrically uniting a stranded wire and a single conductor, a connector body having an internal intermediate tapered bore and adjoining counterbores, one at each end, the one at the smaller end of the bore protecting the insulation of the single conductor and the other being threaded, a clamping device fitting within the tapered bore and adapted to clamp the single conductor and a bolt permanently united to the stranded conductor and fitting the threads of the counterbore to set the clamping member against the single conductor by pressure longitudinally against the clamping member. 120
